UNITED STATES PATENT OFFICE.

BENJAMIN F. HARTWELL, OF WINCHESTER, MASSACHUSETTS.

BOOT OR SHOE, COMPOSITE SOLE THEREFOR, AND METHOD OF MAKING.

Application filed April 27, 1926. Serial No. 104,975.

My present invention relates to novel boots or shoes, composite soles for use therewith, and the method of making said soles.

The present invention is an improvement over the shoe and sole illustrated in my prior and copending application Ser. No. 79,992, filed January 8, 1926, and utilizes the novel form of interlocking joint described in said application, as well as in my prior and copending application Ser. No. 56,145, filed September 14, 1925.

In developing this art, however, I have discovered that it is desirable and essential to provide some further stitch retaining means between the composite sole and the shoe to which it is attached, than merely the midsole of combined rubber or rubber composition and crepe rubber. To this end I have devised the novel shoe, and composite sole, illustrated in the drawing herein.

The stitch retaining means may consist in a layer of thin upper leather, or split leather, canvas, or any other material which will have sufficient strength to assist in holding the stitching. In a welt shoe this stitch retaining layer would be between the combined midsole and the welt, and in a McKay shoe it would be between the combined midsole and the upper.

Since the point of greatest wear and strain on the stitches comes at the toe portion of the shoe, I preferably apply my stitch receiving and reinforcing layer at the toe portion only, extending a sufficient distance from the point of the toe to afford a substantial reinforcement. I may also, if desired, carry this stitch receiving and reinforcing layer throughout the entire length of the combined midsole, to the shank portion of the sole or to the interlocking point.

In manufacturing a boot or shoe under my novel method, the composite sole is first formed, comprising a leather shank and heel portion to which is attached, by means of the novel interlocking joint described in my said prior applications, a rubber or rubber composition forepart layer having secured thereto, as by cementing, a midsole of crepe or latex rubber. To the upper surface of the rubber or rubber composition layer I then cement or otherwise attach my novel stitch retaining and reinforcing layer, either for the toe portion of the shoe, or extending substantially the full length of the rubber or rubber composition layer. These com-

bined forepart layers are then united to the leather shank and heel portion, at the interlocking joint, by stitching and cementing, so that a strong and wear resisting joint is provided, preferably in a non-flexing part of the shank of the shoe.

This novel composite sole, thus formed and united, is then attached to the shoe, either welt or McKay, by stitching, or other mechanical fastenings, whereupon an outsole, preferably of crepe rubber, is united to the crepe midsole by the well-known "two-unit" process, wherein the outsole is unified with the midsole, by partially dissolving the contacting surfaces, or one of them, of the midsole and outsole, and applying together, under pressure, until unified.

In the novel shoe thus constructed, I secure the full flexibility of the forepart and wear resisting qualities of the crepe rubber, combined with the advantages of a leather shank and heel seat portion, together with the further assurance of the additional reinforcement provided by my novel stitch retaining member at the toe or forepart.

Further features of the invention, details and advantages, will be hereinafter more fully pointed out and claimed.

Referring to the drawings, illustrating a preferred embodiment of my present invention,

Fig. 1 is a side elevation of a welt shoe embodying my present invention;

Fig. 2 is a fragmentary side elevation of a similar shoe with a full length reinforcing layer;

Fig. 3 is a bottom plan view of the composite sole;

Fig. 4 is a cross-sectional view of the forepart of a welt shoe, illustrating my novel stitching retaining layer in position; and

Fig. 5 is a similar cross-sectional view of a McKay shoe.

While my invention resides primarily in the sole and method of joining same, I also consider that I have effected a substantial and novel improvement in the boot or shoe structures, whether of welt or McKay type, and therefore I wish to claim all of these features herein.

Fig. 1 illustrates, in side elevation, a conventional welt shoe of the oxford type, wherein the upper 1 has joined to it a welt 2. A fiber or rubber sole member 3, to which is secured a midsole 4 of thin crepe

rubber, is then attached to a leather sole member 5 of an area to extend over the shank and heel seat of the shoe. The rubber or fiber sole 3 and midsole 4 of crepe rubber are joined in any suitable manner, by solvents, cements, or the like, and each secured to the leather sole portion 5 in a scarf 6, provided therefor, in any suitable manner, preferably by stitching 7 and reinforced by cement. The reinforcing layer 8 is also secured to this composite sole, preferably by cementing. The layer 8 may be of any desired material of sufficient strength to assist in the retaining of the stitches and to 15 also act as a reinforcement, such as thin split leather, upper, leather, canvas or the like. The composite sole, as thus far described, is then secured to the shoe in the usual manner, as by stitching or other mechanical fastenings, heel-seat nailing, etc. With this composite sole secured to the shoe, an outsole 9, preferably of crepe rubber, is then joined to the midsole 4 in the usual manner, preferably by coating the contacting surfaces of 20 the soles 4 and 9 with a suitable solvent, such as benzol, and assembling the two soles together, preferably under pressure, until the outsole 9 has unified with the midsole 4 in a firm, homogeneous manner, forming a neat, 25 attractive, firm, strong and efficient shoe structure, and one of great wear-resisting capacity. A conventional heel 10 is illustrated in Figs. 1 and 2, which may be of rubber, leather or the like. As shown in 30 Fig. 1, the jointure of the leather and rubber sole members comes substantially at the arch of the shoe, away from the flexing or bending of the sole in walking, and being thus relieved of any liability of breaking away 35 caused by such strains.

Fig. 2 illustrates substantially the same structure described in Fig. 1, with the exception that I may desire to add a layer 11 of the same material as the layer 8 in Fig. 45 1, the layer 11 extending substantially the length and area of the rubber or composition layer 3. The method of constructing the composite sole, and attaching same to the shoe, would be the same as described for 50 Fig. 1.

Fig. 3 illustrates, in cross-section, the method of attachment of my novel sole to a shoe of the welt type, wherein the upper 1, welt 2, and insole 12 are united by inseam 55 stitching 13. To the welt is then attached the composite sole comprising the layer 8 or 11, rubber or fiber sole 3, and midsole 4, by welt stitching 14. The outsole 9 is illustrated as unified with the midsole 4.

Fig. 5 illustrates the method of attachment to a McKay shoe, wherein the upper 1, insole 15 and composite sole 8, 3 and 4, are all united by through and through stitching

16, the outsole 9 being shown unified to the crepe midsole 4.

The advantages of thus having the stitching holding the composite sole, concealed under the outsole 9, and therefore not subjected to wear, will be readily appreciated.

While I have necessarily described my invention somewhat in detail, it will be appreciated that I am not limited thereto, but may vary the size, shape and arrangement of parts within reasonably wide limits without departing from the spirit of the invention.

My invention is further described and defined in the form of claims as follows:

1. A composite sole, comprising a leather shank and heel portion, a forepart composed of a layer of rubber or rubber composition to 80 which is adhered a midsole of crepe rubber, an interlocking transverse joint between the leather sole portion and both said rubber layers in a non-flexing part of the arch or shank, and a stitch-retaining and reinforcing layer on the upper toe portion of said forepart.

2. A composite sole, comprising a leather shank and heel portion, a forepart composed of a layer of rubber or rubber composition to 90 which is adhered a midsole of crepe rubber, an interlocking transverse joint between the leather sole portion and both said rubber layers in a non-flexing part of the arch or shank, and a stitch-retaining and reinforcing layer on the upper surface of said forepart.

3. An improved boot or shoe, having a composite sole comprising a leather shank and heel portion, a forepart composed of 100 a layer of rubber or rubber composition to which is adhered a midsole of crepe rubber, an interlocking transverse joint between the leather sole portion and both said rubber layers in a non-flexing part of the arch or shank, a stitch retaining and reinforcing layer secured to the upper surface of said forepart, said composite sole being secured to the shoe by mechanical fastening devices, and a crepe rubber outsole unified with said 110 crepe rubber midsole and concealing and protecting the mechanical fastening devices in said midsole.

4. The improved process of making composite soles, which consists in uniting a layer 115 of rubber or rubber composition with a midsole of crepe rubber, uniting said joined layers with a leather shank and heel portion in a transverse interlocking joint by stitching and cementing, and securing a stitch-retaining and reinforcing layer on the upper 120 surface of said composite sole.

In testimony whereof, I have signed my name to this specification.

BENJAMIN F. HARTWELL.
